David D. Rawson of Waco in State of New Hampshire

Letters Patent.

The schedule referred to in this Letter Patent and making part of the same, containing a description in the words of the said David D. Rawson himself of his improvement called the grooving machine -

This machine operates in an oblong frame one foot wide and three feet ^{long} by means of pulleys and bands. The frame consists of two foot pieces, twenty inches long, five posts, two of which are two feet eight inches high, two of one foot eight inches with a cap piece, and the other standing centrally between the two posts last mentioned about three feet high, halved on the cap piece and forced into the foot-piece below, one inch exclusive between the two highest posts, on a level with the cap piece upon the other posts, and four girts lengthwise, the two lower of which are forced into the posts about four or five inches above the foot pieces, the other about one foot higher, all these timber may be two inches square. The principal pulley or wheel is twenty four inches in diameter, and is moved by a crank, the shaft of which rests upon the two upper ^{girts} of the frame, three or four inches from the middle and secured by caps, is placed about one inch or more within one of the girts, and about five or six inches within the other the said pulley being about one or one and a half inch in thickness. The other pulleys, the one four the other eight inches, in diameter, are fixed upon a revolving shaft, the ends or guides of which are inserted into the two longest posts about one inch and a half from the top.

The smallest of these, the four inch pulley is placed in a direct line with the largest pulley or wheel just mentioned, about two inches or more from which the eight inch pulley is placed upon the same revolving shaft, - on the outside of the fifth or

on centre post, being the highest post in the apparatus from which is affixed the wood cutter or groover and stands perpendicular, the cutter with its arbor or spindle is made of cast iron, is five or six inches long and about three sixteenths of an inch in diameter. The diameter may however be varied according to the width of the groove intended to be cut. — Upon the spindle is a pulley or whell of wood about three inches in diameter. This spindle, or arbor of the cutter, is fixed in a frame of cast iron or brass formed of a plate of about five inches in length, two in width, and one fourth, an inch thick fastened on to the outside of the posts by screws, — extending from which at right angles at the top and near the bottom, are two arms the upper of which is two inches long, one inch wide five-eighths thick, and rounder on the top; the lower three inches and five-eighths long, one inch wide and one fourth of an inch thick through holes in both of which, near the outer end, the perpendicular spindle or arbor of the cutter passes and receives, under the lower arm is affixed and secured by screws a bearing of iron or brass through which the spindle of the spindle at the lower end passes secured underneath the bearing by a washer and pin to prevent its rising, and on the top by the shoulder of the spindle to prevent its lowering. — By means of the screws which hold it in its place, the bearing may be raised or lowered to suit the depth of the groove intended to be cut. On the upper arm is fixed a moveable gauge, to regulate the thickness of the moulding. — The cutter or groover is operated by means of two leather bands applied to the pulleys, one extending from the large or twenty four inch to the four inch pulley, and enclosing them two, and the other from the eight inch to the three inch pulley or whell of the arbor of the cutter. The eight inch pulley moves perpendicularly, and the whell horizontally, the band enclosing them is necessarily twisted; and in order that it may not slip or run off of the whell, the whell must be so placed

153

upon its shaft (the arbor of the cutter) that the center of its plane or thickness shall be exactly level with the highest part of the periphery of the eight inch pulley, and the eight inch pulley must be so placed upon its shaft, that the periphery of the wheel opposite to the crank of the large or 24 - inch wheel shall be in a direct line with the center of the plane of the eight inch wheel.

To use the cutter, the material in which the groove is to be cut must be held in the hands immediately over and upon the cutter, pressing it at the same time against the gauge and pushing the material forward by the hand as the groover cuts - somewhat in the manner the material is moved when applied to a circular saw, conforming the groove to the straight or curved edge or side of the material in which it is cut.

The cutter or groover, made of cast steel has two spiral edges, winding half round, with an edge at the top, the top of its diameter made crooked, or resembling in form a swallow tail, cutting at the same time with its upper and lateral edges.

The invention which I claim, is the spiral cutter or groover, and the combination and arrangement of the machinery to effect its use, - By the use of this cutter grooving of any kind may be done with great expedition with at least seven times the rapidity that it is usually done with a chisel, or in any other way heretofore known or practised. It may be operated by hand, by water, steam, or any other power.
